SAFETY GUARD FOR PRESSES

Paul J. Murcko, Bridgeport, Conn.

Application March 20, 1945, Serial No. 583,759

2 Claims. (Cl. 74—615)

1

This invention relates to guards for punch presses and the like, and more particularly to guards of the type in which a pendant arm swings across the front of the die-space, to ensure that the hands of an operator are out of the way of the tools in the press.

An object of the invention is to provide an improved pendant or swinging type guard for punch presses and the like which is quick acting, efficient and reliable, and extremely simple in construction.

Another object of the invention is to provide a pendant-type guard which may be easily fabricated of but few, simple parts, and which may be conveniently and quickly installed on various types of presses.

Still another object of the present invention is to provide a pendant guard of simple construction which may be quickly adjusted after installation, to provide the proper desired action.

These and other objects are accomplished in the embodiment of the invention illustrated herein by a novel structure wherein a pendant guard arm is pivotally mounted at the center of the press in front of the ram, and actuated by a linkage fixed to the ram, and connected to the arm through a sleeve or collar connection slidable on the latter. By this construction but comparatively few parts are required to obtain a full sweeping action of the arm in response to the vertical reciprocation of the ram.

Adjustment of the device is effected in an extremely simple manner, by shifting in either of various directions the position of the link fixedly carried by the ram, the mounting for the link being made adjustable for this purpose.

Since but few parts are employed, and since the operation and movements are extremely simple, the device is reliable in use, and will not get out of order easily. The various parts may be made up quickly of stock readily available, so that the device is economical to fabricate.

Other features and advantages will hereinafter appear.

In the accompanying drawings:

Figure 1 is a front elevation of a press and guard made according to the invention, the ram of the press being in raised position, and dotted lines indicating the lowered position of the ram, and the corresponding position of the guard arm.

Fig. 2 is a fragmentary top view, partly in section, of the press and guard.

Fig. 3 is a section on the line 3—3 of Fig. 1, and Fig. 4 is a section on the line 4—4 of Fig. 1.

Referring to Figs. 1 and 2, a punch press 10 is

2

shown having a ram 11 vertically movable between guides 12 secured to the press frame 13. The ram 11 may have a plurality of punches 14 for cooperation with dies 15 secured to the bed 10a of the press. Usually the punches 14 are carried by a block or base 16 which is secured to the ram 11 by screws 17.

The guard of this invention is of novel and simple construction, and comprises a pendant or 10 guard arm 18 which is preferably formed of round bar stock such as cold rolled, a diameter of approximately $\frac{3}{8}$ " being suitable in most cases. The arm 18 is formed generally in the shape of an L, with a slight deviation to be noted.

15 As seen in Fig. 1, the longer depending portion 18a of the arm has a reverse bend 18b to enable the bend 18c of the L, which is made with a fairly large radius, to cover an arc greater than 90° .

Nested within the bend 18c is a hub 19 of generally polygonal outline, the hub being welded to the arm as indicated by the crossed lines, and the weld subsequently ground smooth.

The hub 19 is apertured to receive a stationary pivot screw 20 having a washer 21 under its head, 20 the screw being threaded into a Z-mounting bracket 22, Figs. 1, 2 and 3, and being locked at the rear of the bracket by a nut 23.

Referring to Figs. 1 and 2, the bracket 22 is secured by a screw 24 and dowel 25 to the frame 30 13 of the press, and is so shaped that the pivot screw 20 is located approximately midway between the guides 12, and in front of the ram 11.

By this construction the long portion 18a of the guard arm 18 may be moved about the pivot 35 screw 20 so that it sweeps across the front of the die-space 26 between the ram 11 and the press bed 10a.

For the purpose of actuating the guard arm 18 to cause it to travel across the front of the die-space 26 in response to reciprocation of the ram 11, according to the invention, a novel operating means is provided comprising a collar 27 adapted to be slidably carried by the operating portion 18d of the guard arm 18. The collar 27 has a stud 45 28 extending radially from the bore, the stud having a smooth bearing portion 28a and a threaded portion 28b which latter carries a nut 29.

Connecting the collar 27 with the ram 11 is a 50 link 30 formed of flat stock, shaped by means of a pair of reverse bends 30a and 30b so that its ends are offset from each other. Both ends of the link 30 are apertured, one end having an elongate aperture or slot 30c and the other a round aperture 30d through which latter the stud

28 of the collar 27 extends. The nut 29 on the stud prevents inadvertent removal of the latter from the link, a locking set screw 31 being provided in the nut 29 as shown in Fig. 5.

The slotted end of the link 30 is secured by screw means to the ram 11 of the press, preferably the screw means being one of the screws 17 used to secure the punch block 16 to the ram. A washer 31 is provided between the head of the screw 17 and the link 30, as shown.

By tightening the screw 17, which is usually of substantial size, the link 30 may be rigidly secured in place on the ram 11 against movement with respect to the latter. Therefore when the ram 11 is moved vertically, the link 30 will also move, causing swinging of the guard arm 18 about the pivot screw 20, accompanied by sliding of the collar 27 on the arm portion 18d. This sliding occurs since the arm portion 18d travels in an arc, whereas the link 30 is fixed on the ram 11 and does not swing but moves solely translationally.

Adjustment of the guard is very simple. The amount of travel of the arm 18 for a given stroke or travel of the ram 11 is adjustable by loosening the screw 17 and changing the angular position of the link 30 with respect to the ram, after which the screw is again tightened. By varying the angular position of the link, the distance between the path of travel of the collar 27, which path is a straight line, and the pivot screw 20 is varied, thereby altering the average leverage between the link and the arm 18.

To adjust the initial and final positions of the arm 18, shown in Fig. 1, use is made of the slot 33c in the link, the latter being shifted longitudinally as permitted by the slot at the time that the angular position of the link is being adjusted.

Thus, the guard may be quickly and conveniently adjusted to suit the particular press on which it is installed, and to accommodate it for use with one die set, or with the multiple die set shown.

After the proper adjustment has been effected, the link may be positively locked in position by drilling and tapping for a locking screw 32, Fig. 1, if desired.

The guard structure provided by this invention is simple and economical to produce, consisting of but few parts, having a simple, foolproof linkage. It may be quickly adjusted to suit any press and to provide a wide sweep or travel of the arm

18, so that safety and proper functioning is assured, and may be easily locked in this adjustment.

Variations and modifications may be made within the scope of this invention and portions of the improvements may be used without others.

I claim:

1. The combination with a press of a guard arm having a rigid pivot intermediate its ends, mounted in a fixed location with respect to the press frame, one part of said arm extending downward from the pivot whereby the lower end is movable across the front of the die-space of the press without transmitting flexure to the other part of the arm; a link rigidly secured to the ram of the press; and means slidable on the other part of the arm, and pivotally connected to the link for causing the arm to sweep across said die-space when the ram is lowered and raised, both said arm parts normally extending to one side of a plane passing vertically through the axis of the pivot.

2. A press guard comprising a depending guard arm having a rigid pivot adjacent its upper end, and an extension above the pivot, projecting laterally substantially at right angles to the arm; means for mounting the pivot on the frame of the press so that it is located in front of the press ram; a collar slidably carried by said extension; a link pivotally connected to the collar; and means for rigidly fastening the link to the ram of the press whereby, when the guard is installed on the press, raising and lowering of the ram will cause the guard arm to sweep across the front of the die-space of the press without transmitting any flexure of the arm to the extension, said arm and extension normally extending to one side of a plane passing vertically through the axis of the pivot.
